George C. Heinrich
ATTORNEY

UNITED STATES PATENT OFFICE

NATHAN MICHELMAN, OF BROOKLYN, NEW YORK

GRATING

Application filed November 30, 1928. Serial No. 322,651.

My invention relates to improvements in gratings, particularly jail door and window gratings and the like, and it is the principal object of my invention to provide a grating 5 of simple and comparatively inexpensive construction which can be readily assembled and which is comparatively tool-proof and cannot be readily cut or drilled or otherwise tampered with or removed.

10 Another object of my invention is the provision of a novel grating construction readily manufactured from hardened and tempered chrome or otherwise tough or cohesive material the bars of which are readily 15 and firmly locked in place.

A further object of my invention is the provision of a jail grating provided with means for firmly locking the cross and vertical bars in their adjusted and locked position without showing traces of the manner in 20 which the several series of bars are interlocked at their points of intersection.

These and other objects and advantages 25 of my invention will become more fully apparent as the description thereof proceeds and will then be specifically defined in the appended claims.

In the accompanying drawing forming a material part of this disclosure:

30 Fig. 1 is a fragmentary front elevation of a grating constructed according to my invention.

Fig. 2 is a detail top view of one of the cross bars of the grating before the introduction of the vertical bars into the holes 35 of such bars.

Fig. 3 is a section on line 3—3 of Figure 2.

Fig. 4 is a view similar to Figure 2, but 40 showing the manner of introducing the vertical bars.

Fig. 5 is a section on line 5—5 of Figure 4.

Fig. 6 is a fragmentary front elevation of 45 one of the vertical bars of the grating.

As illustrated, the grating according to my invention, like most gratings, consists of a series of parallel vertical bars 10 and a series of horizontal bars 11, preferably arranged at

50 right angles to each other.

These bars are preferably made of hardened tempered steel so as to make them tool-proof, and may have any desired, suitable cross-section, preferably circular.

The horizontal or transverse bars are each 55 provided with a plurality of openings 12 allowing the passage of the vertical bars, and each of said openings is equipped with an inner groove 13 ending in a recess 14 in communication with the opening 12.

The vertical bars have each at a suitable 60 point corresponding to the location of the cross-bars protuberances or knobs 15 adapted to fit into the recess 14 and inner groove 13.

The operation of my device will be entirely 65 clear from the above description and it will be clear that in assembling the bars of the grating, the horizontal bars 11 are first placed at suitable distances apart, and then the vertical bars 10 are passed through the openings 12 in the transverse bars until their knobs 15 are in position to engage the recesses 14. If now the vertical bars are rotated for about 90° around their longitudinal axis 70 their knobs 15 will slide in the grooves and firmly connect vertical and horizontal bars. If now the recesses 14 are closed by a wire 75 or the like suitable material 16, inserted into grooves 13 on the underside of horizontal bars 11 through recesses 14 and cut off, the grating will present a finished appearance 80 and constitute a solid grating which, being of hardened preferably chrome steel cannot be readily cut or drilled and if set between the sill and top of a window, or floor and ceiling 85 of a room cannot readily be removed.

It will be understood that I have described and shown the preferred form of my invention as example only of the many possible ways to practically construct my novel and improved grating and that I may make such changes in its general arrangement and in the construction of the minor details thereof as come within the scope of the appended claims without deviation from the spirit of 90 my invention or the principles involved.

Having thus described my invention, what I claim as new, and desire to secure by Letters Patent is:

1. A grating comprising a plurality of 100

horizontal bars, each having a plurality of openings in spaced relation, an inner groove formed in said openings, and a peripheral recess formed in the wall of each opening in communication with said groove, a series of vertical bars, a plurality of protuberances on each of said vertical bars adapted to be entered into the recesses of said horizontal bar openings and to be rotated in the groove thereof, and a wire entered into said recess to lock the vertical and horizontal bars at their points of intersection.

2. A grating comprising a plurality of series of intersecting horizontal and vertical bars, each of said horizontal bars formed with a plurality of juxtaposed openings allowing the passage of the vertical bars, the walls forming said openings having an inner groove formed therewith, and said horizontal bars having formed therein recesses in communication with said openings and grooves, a plurality of knobs on each of said vertical bars adapted to enter said recesses and grooves and to slide in the latter upon the rotation of said vertical bars about their longitudinal axes, and wires entered into said recesses to lock said vertical bars and horizontal bars in their relative adjusted positions.

Signed at Brooklyn, in the county of Kings and State of New York, this 23rd day of November, A. D. 1928.

NATHAN MICHELMAN.
